UNITED STATES PATENT OFFICE

2,133,704

TOOTH BRUSH

Fred A. Jones, Los Angeles, Calif., assignor to
 Clean-Be-Tween Toothbrush Co., Inc., New
 York, N. Y., a corporation of Missouri

Application September 11, 1936, Serial No. 100,224

2 Claims. (Cl. 306—30)

My invention relates to toothbrushes and more particularly to an improved holder for toothbrushes having adjustable and replaceable brush heads.

5 An object of my invention is to provide a holder embodying improved clamping means for the adjustable retention of a brush head which permits the brush head to be readily moved to any desired angular position with respect to the holder and frictionally retained in its adjusted position.

A further object is to provide a brush holder which permits of the facile attachment and removal of a separable brush head.

A marked objection to prevailing clamping means for purposes analogous to that of the construction herein described is the fact that such clamps present openings and recesses which are prone to become filled with dentifrice and foreign matter which clog the assembly and renders the 20 same unsanitary.

An important object of the present invention is to provide an improved clamp structure for the described purpose wherein no recesses or pockets which tend to accumulate undesirable matter are present, and which is devoid of projections or other sources of potential injury to the oral cavity and gums.

The immediate object of my invention is to provide a holder having an improved clamping device for securing thereto a brush head of the type described in U. S. Letters Patent No. 1,835,-320, of December 8, 1931.

Further objects and advantages of the brush holder constructed in accordance with my invention will be apparent from the following detailed description and accompanying drawing in which:

Fig. 1 is a side view of a toothbrush constructed in accordance with my invention;

Fig. 2 is a longitudinal sectional view through the brush head clamping structure, the section being taken at line 2—2 of Fig. 1;

Fig. 3 is a longitudinal sectional view taken at line 3—3 of Fig. 2, and

Fig. 4 is a transverse sectional view taken at line 5 4—4 of Fig. 3.

Referring now by characters of reference to the drawing, the handle or brush holder includes an elongated grip 5, and a brush clamping assembly, denoted generally 6, at one end of grip 5. Grip 5 may be constructed of any suitable material having the requisite strength but preferably comprises a molded plastic formed cylindrically at the end adjacent the clamping means, and being flattened and slightly curved at the opposite end

to conform to the user's hand and provide a comfortable gripping surface.

The clamping assembly 6 is rigidly and permanently secured to the gripping part 5 by means of an axial extension 7 on the inner end of a shaft 8, which extension may be embedded in the grip 5 when the latter is molded or secured by cement or other suitable means. A metal ferrule 9 is provided on the outer end of grip 5 for purposes of strengthening and enhancing the appearance of the same.

The shaft 8, of lesser diameter as compared to the outer end of grip 5, extends into an enlarged end portion 10 of a tube or sleeve 11 and is rigidly and permanently secured thereto. The shaft 8 is provided with a diametral slot 12 which extends longitudinally between the inner end of sleeve 11 and ferrule 9. An axial bore 13 extending from slot 12 to the outer extremity of the shaft provides a passage for a clamping element 14.

The clamping element 14 is preferably constructed of heavy gauge, resilient wire and includes an arm which extends through sleeve 11 and through bore 13, terminating at its inner end within slot 12. Fixedly secured to the inner end element 14 is a small metal block 16 which is fitted to, and adapted for longitudinal sliding movement within slot 12. The block 16 is provided with external threads 17.

Mounted for rotation about the slotted portion of shaft 8 is a collar 18 having internal threads which operatively engage threads 17 on block 16. Collar 18 fits closely and fills out the reduced portion of the toothbrush handle, such reduced portion being constituted by shaft 8, and accordingly results in a handle which is relatively smooth and regular throughout its length.

The clamping member 14 projects outwardly beyond the end of sleeve 11 where it is provided with a crook 19 which is adapted to embrace the upstanding stud 20 of a brush head 21 described in Patent No. 1,835,320, hereinbefore mentioned. The extreme end 22 of crook 19 projects backwardly into the mouth portion of sleeve 11 which is flared to receive the same.

It will now appear that rotation of the collar or nut 18 in the proper direction results in the outward or inward movement of the clamping element relative to sleeve 11, which consequently results in the expansion or contraction of loop 19. By the means described, loop 19 may be enlarged sufficiently to free the same from the stud 20 to permit removal and replacement of the brush head, and may be constricted about the

stud to rigidly clamp the brush head in any desired angular position.

From the foregoing description of my improved clamping assembly it may be observed that the 5 component parts thereof are inseparably interconnected and accordingly none of the parts can become lost. The closed construction prevents dentifrice and foreign matter from entering the mechanism, to clog and render the same 10 unsanitary.

I claim:

1. A toothbrush structure comprising a handle and a removable brush head, said handle including a slotted shaft, a sleeve projecting axially from one end of said shaft and rigidly connected thereto, an elongate element movable in said sleeve, said element terminating at one end in a crook adapted to embrace and frictionally clamp 15 a portion of the brush head when the element is drawn inwardly of said sleeve, an externally threaded block disposed for movement in the shaft slot, secured to the opposite end of said element, and an internally threaded collar disposed about the slotted portion of said shaft and 20 25

operatively engaging said block, said collar providing a closure for the shaft slot.

2. A toothbrush structure including a brush holder and a removable brush head having an anchoring stud, said holder comprising an elongated grip, a shaft fixedly secured to and extending axially from one end of said grip, said shaft being of lesser diameter than that of the adjacent end portion of the grip and having an intermediate, longitudinally extending slot and 10 an axial bore extending from said slot to the outer extremity of the shaft, a sleeve forming a continuation of said shaft having its inner end rigidly secured about the outer end of said shaft, a resilient clamp at the outer end of said sleeve 15 adapted to be drawn toward the sleeve to cause its constriction about the brush head stud, an arm extending from said clamp through the sleeve and shaft bore, an externally threaded block fixed to said arm and movable in the shaft 20 slot, and an internally threaded collar on the shaft operatively engaging said block, said collar providing a continuous, regular external surface for the holder between the sleeve and grip.
